UNITED STATES PATENT OFFICE.

WILLIAM GEORGE HAMMOND, OF CLEVELAND, OHIO.

WINDOW SCREEN.

Application filed November 21, 1922. Serial No. 602,322.

To all whom it may concern:

Be it known that I, WILLIAM G. HAMMOND, a citizen of the United States, residing at Cleveland, in the county of Cuyahoga and State of Ohio, have invented certain new and useful Improvements in Window Screens, of which the following is a specification.

My invention relates to improvements in window screens, and specifically, to the sliding type of screen wherein the sliding sashes are adapted to have screen members secured thereto, the movement of these screen members to be controlled by the raising and lowering of the sliding sashes, and means being provided in the wall of the building and in alignment with the upper and lower ends of the window frame for receiving the screens therein, when the windows are in a full, or partially closed position.

An object of the invention resides in the provision of an improved coupler whereby a window screen may be readily attached to or detached from a sliding sash in a novel and expeditious manner for allowing the sliding sash to be operated without occasioning an operation of the screen, and for further allowing the screen to be removed from the window frame, for repairing, etc.

With these general objects in view and others that will appear as the nature of the invention is better understood, the same consists in the novel construction, combination and arrangement of parts hereinafter more fully described, illustrated in the accompanying drawings, and pointed out in the appended claim.

In the drawings forming part of this application, like numerals of reference indicate similar parts in the several views, and wherein:

Figure 1 is an elevation of a window casting together with the sliding sashes therein, a portion of the building wall being broken away for more clearly disclosing the position of the screen members with respect to the sliding sashes.

Figure 2 is a vertical cross sectional view of the structure shown in Figure 1.

Figure 3 is a detail, fragmentary enlarged sectional view of the upper sliding sash having the upper sliding screen connected thereto.

Figure 4 is a vertical sectional view upon the line 4—4 of Figure 3, and

Figure 5 is a view similar to Figure 4, but taken upon the line 5—5 of Figure 1.

Referring to the drawings, the usual building wall A is shown as having formed or otherwise disposed therein, a window frame B having the usual upper and lower sliding sashes therein as C and D respectively.

The building wall A is so constructed as to form an upper and lower pocket 1 and 2 therein, which pockets are in alignment with the upper and lower sills of the window frame, as more clearly shown in Figures 1 and 2. The lower frame bar "d" of

the lower sliding sash D is adapted to have close contact with the upper frame bar of a substantially rectangular screen member 3 and pivotally secured centrally upon this frame bar "d" of the said sash is a link 4, 75 which link is of angular formation as more clearly shown in Figure 5 so as to extend inwardly upon the projecting edge of the frame bar "d" and thence downwardly and having a circular shaped plate or head portion 5 thereon. It is of course to be understood that the thickness of the frame of the screen 3 is less than that of the frame bar "d" of the sliding sash D so as to allow the outer surface of the screen to be flush with

the outer surface of the window frame so as to permit the inner portion of the window frame to project beyond the adjacent surface of the screen so as to allow this projecting portion of the window frame to contact 90 with the window sill as shown in Figure 1. Set with a mortise in the upper frame bar of the screen 3 is a substantially rectangular plate 6, which plate is so disposed as to lie substantially beneath the pivoted link 95

4 of the frame bar "d" of the lower sash. This plate 6 is suitably cut away as at 7 for allowing the disk or head 5 of the link 4 to snap therein as shown in the figures, for effectively connecting the screen to the sash 100 whenever it is desired that the screen be raised or lowered with the raising or lowering movement of the sash. The head or disk 5 of the link 4 has formed thereon, a relatively small projecting finger 6' for 105 readily allowing this disk to be disengaged from the opening in the plate 6.

The upper sliding sash C also carries a screen 3', the bottom frame bar of which, normally rests upon the upper frame bar of the sliding sash and when connected to the sash in a manner hereinafter described, the

same is adapted to slide out of and into the pocket 1 whenever a sliding movement of the sash is occasioned. Referring to Figure 4, the lower frame bar of the screen 3' has 5 a link 4' pivotally secured thereto, and adapted to extend downwardly over the adjacent surface of the upper frame bar of the sash C. This frame bar of the sash is also suitably mortised so as to receive a sub- 10 stantially rectangular plate member 6', which plate has a suitable opening formed therein for receiving the disk or headed end 5' of the link 4'. In view of the latter mentioned construction, it will be readily 15 appreciated that the headed or disked end 5' of the link 4' may be snapped into the opening in the plate 6' for rigidly connecting the said screen to the sash.

The height of the lower screen 3 is relatively greater than the height of the upper screen 3' and it is of course to be understood that suitable slots are provided in the upper and lower sills of the window frame B for permitting of a sliding movement of 20 these screens into their receiving pockets 1 and 2. The lower screen 3 when connected to the sash D functions as a usual window screen when this sash is raised and the upper screen 3' constitutes a ventilating screen 25 when the sash C is moved to a position sub-

stantially as shown in Figures 1 and 2. In view of the detachable coupling means between the screens and sashes, it will be seen that the sashes may be readily raised or lowered without occasioning an operation of the 35 screens and further, by releasing these catches, the screens may be readily removed for rewiring, etc.

What I claim as new is:—

In combination, a frame, a pair of slide- 40 able sashes in the frame, a coupling comprising a plate embedded in the face of one sash to be flush therewith, and having a slot leading in from one of the side edges thereof and provided at its inner end with a circular enlargement, a second plate embedded 45 in the face of the other sash to be flush therewith, and a link pivotally mounted upon the second mentioned plate and having a head adapted to seat in the enlargement of the 50 slot, and a shank adapted to seat in the outer portion of the slot, said link completely filling the slot and the enlargement thereof, and the outer surface of the link lying in the same plane as that occupied by the outer surface of the slotted plate, when the link is engaged in the slot and the enlargement 55 thereof.

In testimony whereof I affix my signature.
WILLIAM GEORGE HAMMOND.
